US00D816112S

(12) **United States Design Patent** (10) **Patent No.:** **US D816,112 S**
Toth (45) **Date of Patent:** **** Apr. 24, 2018**

(54) **DISPLAY SCREEN WITH GRAPHICAL USER INTERFACE**

(71) Applicant: **Gamblit Gaming, LLC**, Glendale, CA (US)

(72) Inventor: **Edvard Toth**, Santa Monica, CA (US)

(73) Assignee: **Gamblit Gaming, LLC**, Glendale, CA (US)

(**) Term: **15 Years**

(21) Appl. No.: **29/580,934**

(22) Filed: **Oct. 14, 2016**

Related U.S. Application Data

(63) Continuation of application No. 29/531,976, filed on Jun. 30, 2015.

(51) **LOC (11) Cl.** **14-04**

(52) **U.S. Cl.**

USPC **D14/488**; D14/486

(57) **CLAIM**

The ornamental design for a display screen with graphical user interface, as shown and described.

DESCRIPTION

FIG. 1 is a front view of a display screen with graphical user interface, showing a first embodiment of the new design; and,

FIG. 2 is front view of a second embodiment thereof. The broken line showing of the display screen form no part of the claimed design. The broken line showing of portions of the graphical user interface form no part of the claimed design.

1 Claim, 2 Drawing Sheets
